UNITED STATES PATENT OFFICE.

ALBERT E. GOULD, OF GRAND RAPIDS, MICHIGAN, ASSIGNOR TO AMERICAN METAL WEATHER STRIP COMPANY, OF GRAND RAPIDS, MICHIGAN, A CORPORATION OF MICHIGAN.

WEATHER-STRIP.

1,136,794.

Specification of Letters Patent. Patented Apr. 20, 1915.

Application filed December 30, 1912. Serial No. 739,323.

To all whom it may concern:

Be it known that I, ALBERT E. GOULD, a citizen of the United States of America, residing at Grand Rapids, in the county of Kent and State of Michigan, have invented certain new and useful Improvements in Weather-Strips; and I do hereby declare the following to be a full, clear, and exact description of the invention, such as will enable others skilled in the art to which it appertains to make and use the same.

My invention relates to improvements in weather strips and more particularly to weather strips for windows, and its object is to provide the same with various new and useful features hereinafter more fully described and particularly pointed out in the claims, reference being had to the accompanying drawings, in which:

20 Figure 1 is a horizontal section showing a portion of the sash and casing with my invention applied thereto. Fig. 2 is an enlarged detail of a portion of the weather strip proper. Fig. 3 a perspective of a portion of the fixed member of the weather strip, and Fig. 4 the same of a movable member of the same.

Like numbers refer to like parts in all of the figures.

30 1 represents a portion of the casing, 2 and 3 the edge of the respective sash members of a window, 4 and 5 the stops on the casing.

In the edge of the sash adjacent the casing and nearest to the side toward the opposite sash is a groove 6 in each sash to receive the slidably engaging members of the weather strip. The fixed member 7 is secured at one edge under one of the stops and extends opposite the edge of the sash and 40 nearly across the same to the groove. This furnishes a wide strip secured at one edge only and having considerable flexibility to permit the sash to shrink and swell without objectionable frictional resistance between 45 the movable and stationary parts. The free edge of this strip 7 is bent at right angles to extend into the groove in the sash and is thence returned upon itself forming a channel U-shaped in cross section, with its parallel sides spaced apart to receive a smaller U-shaped portion of a sheet metal member 9 consisting of a strip of thin sheet metal secured to the sash and moved therewith.

This member 9 has one edge secured to the sash and extends across the remaining edge

portion of the same and is fixed thereto and thus moves with the sash when the same is moved to open and close the window, and also horizontally if the sash shrinks and swells. A portion 10 of this strip is folded 60 in U-shape and considerably smaller than the edge 8 of the strip 9 whereby it runs freely within the same.

The base or convex edge of the U-shaped portion 10 engages the concave side of the 65 portion 8 and slides freely thereon. The resilience of the broad portion 7 attached to the casing maintains yieldable connection between the U-shaped portions, and the side clearance therebetween and also the clearance 70 between the portion 8 and the walls of the groove permits free movement of the sash in both directions without binding contact and at the same time the air is effectively excluded from passing the edge of the sash 75 regardless of the amount of clearance between the same and the casing and stops. The air entering this clearance from either direction must, in order to get through, pass into the groove by traversing around on the 80 outside of the portion 8 and thence return in the opposite direction between the two U-shaped portions 8 and 10. In this return movement there is no clearance between the 85 convex side of the portion 10 and the concave side of the portion 8. These two portions having a rocking movement upon each other and also being yieldably held in contact by the resilience of the strip 7, will always be in contact and prevent further passage of the air in either direction and thus 90 secure a complete stoppage of the air passage, and at the same time provide a weather strip that will readily conform to the shrinkage and swelling of the sash and clearance 95 between the same and the casing and stops without in any wise interfering with its effective operation and easy sliding movement when the sash is raised or lowered.

What I claim is:—

1. A weather strip for windows comprising strips of sheet metal each having one edge formed into U-shape, one U-shape portion being smaller than the other and having rocking and sliding movement on the 100 larger U-shape portion.

2. A weather strip, comprising two sheet metal strips each bent at right angles near one edge and thence formed in U-shapes of unequal dimensions, the smaller U-shaped 110

portion being slidable within the larger and out of contact therewith except at the convex base portion of the same which portion engages the concave base portion of the other strip, said strips being respectively attached near their other edges respectively to a window casing and to a window sash.

3. In a combination with a window sash having a groove in its edge, and a window 10 casing, two strips of sheet metal each bent substantially at right angles to extend within the groove and each bent in U-shape within the groove, said bent portions being of different dimensions, the smaller U- 15 shaped portion slidable within the larger U-shaped portion and spaced therefrom at its parallel sides and also engaging the concave portion of the larger one at its convex base portion and slidable therein.

20 4. A weather strip for windows comprising strips of sheet metal each having one edge formed into U-shape, one U-shape portion being smaller than the other and having rocking and sliding movement on the 25 larger U-shape portion at one side only thereof.

5. The combination with a sash having a groove in its edge and a casing for the sash, of a weather strip consisting of two sheets 30 of strip metal one of which is secured at one

edge to the casing and at its opposite edge bent into U-shape with the U-shape portion extending into said groove, the other strip also being bent at one edge to form a U-shape portion which extends into the U-shape 35 portion of the other strip and which has sliding and rocking movement on the latter U-shape portion, the U-shape portion of the first strip being spaced from the walls of said groove.

40 6. The combination with a window and its frame, of a weather strip comprising separate strips of sheet metal secured to the window frame and window, respectively, the adjacent ends of said strips being bent into 45 U-shaped formation, one of said U-shaped portions being smaller than the other and having its bight portion only contacting with the corresponding bight portion only of the other strip for sliding engagement 50 therewith and its side portions spaced from the side portions of the said U-shaped member of the other strip, whereby a rocking movement thereon is permitted.

In testimony whereof I affix my signature 55 in presence of two witnesses.

ALBERT E. GOULD.
